UNITED STATES PATENT OFFICE.

HANS HOHNER, OF NEW YORK, N. Y.

DESIGN FOR A DISPLAY-STAND.

41,688.

Specification for Design.

Patented Aug. 15, 1911.

Application filed March 8, 1911. Serial No. 613,182. Term of patent 7 years.

To all whom it may concern:

Be it known that I, HANS HOHNER, a subject of the German Emperor, residing at New York city, county and State of New York, have invented a new, original, and ornamental Design for Display-Stands, of which the following is a specification, reference being had to the accompanying drawing, forming part thereof.

The figure is a perspective view of a display stand, showing my new design.

The design consists essentially of a square base or pedestal 1 having an upper flange 2 and surmounted by a tapering quadrilateral column 3. This column is provided with a squared upper section 4 having vertical sides that constitute continuations of

the corresponding tapering sides of column 3, from which they are separated by a continuous bead 5. Squared section 4 is in turn surmounted by a quadrilateral pyramid 6 the four triangular sides of which top the corresponding sides of section 4. A second continuous bead 7 which is parallel to bead 5 appears between the top of section 4 and the bottom of pyramid 6.

I claim:

The ornamental design for a display stand, as shown and described.

HANS HOHNER.
